UNITED STATES PATENT OFFICE

2,469,179

REFRIGERATION

Albert Schultze, Evansville, Ind., assignor to
 Servel, Inc., New York, N. Y., a corporation of
 Delaware

Application November 7, 1947, Serial No. 784,597

5 Claims. (Cl. 62—119.5)

1

This invention relates to refrigeration and more particularly to means for insulating and sealing the insulation box of the gas heat exchanger in an absorption refrigerating system of the three-fluid or uniform pressure type.

In domestic refrigerators cooled by absorption refrigerating systems of three-fluid type it is common practice to provide a machinery compartment or flue at the rear of the refrigerator cabinet. In this flue may be located the heat dissipating parts of the system, such as, the absorber and condenser. Also, it is more or less common practice to place the gas heat exchanger of this type of system in the flue. However, when the gas heat exchanger is placed in the flue it is necessary that it be insulated against the relatively warm air that passes up the flue. Furthermore, the insulation box or casing which contains the insulation for the gas heat exchanger should be sealed against the entrance of air into the casing, otherwise the relatively warm moist air passing up the flue is apt to enter the insulation casing causing damage to the insulation and corrosion of the interior of the casing and of the exterior of the gas heat exchanger.

It is therefore an object of my invention to provide an improved method of and means for insulating a gas heat exchanger of a refrigerating system.

It is a further and equally important object of my invention to provide an improved method of and means for sealing an insulation casing around a gas heat exchanger.

The above and other objects and advantages of my invention will be apparent from the following description and accompanying drawing, wherein:

Fig. 1 is a side elevational view, partly in section of a refrigerator incorporating my invention;

Fig. 2 is a vertical sectional view taken on line 2—2 of Fig. 1;

Fig. 3 is a horizontal sectional view taken on line 3—3 of Fig. 2;

Fig. 4 is a detail vertical sectional view taken on line 4—4 of Fig. 2; and

Figs. 5 and 6 are perspective views of top and bottom closure members, respectively.

Referring now to Fig. 1 of the drawing, I have for purposes of illustration shown my invention incorporating a domestic refrigerator indicated generally by reference character 10. This refrigerator includes a low-temperature compartment 11 and a high-temperature or food storage compartment 12, which compartments are cooled

2

by a low-temperature evaporator 13 and a high-temperature evaporator 14, respectively. An insulated partition, not shown, may be located in the upper portion of the cabinet between the low and high temperature evaporators. The cabinet is provided with an outer door 15 for gaining access to the interior thereof. A machinery compartment 16 is located beneath the food storage compartment 12 and a vertical flue 17 extends upwardly from the machinery compartment at the rear of the cabinet. The rear wall of the cabinet is provided with an opening or window surrounded by a frame member 18, which opening is closed by a closure member 19. Closure member 19 includes an inner panel 20 and an outer panel or mounting plate 21, the space between these two panels being filled with a suitable heat insulating material, not shown. A gas heat exchanger 22 is located in the vertical flue 17 and is connected at its upper end by suitable conduits, not shown, to the low and high temperature sections of the evaporator. At its lower end the heat exchanger is connected to the inlet and outlet ends of an absorber, not shown. Only so much of the refrigerating system as is necessary for a complete understanding of my invention has been illustrated in the drawings.

In accordance with my invention, the mounting plate 21 is provided with a rectangular opening 23, which opening is surrounded by an inwardly projecting flange 24. My improved insulation box includes an elongate channel member 25 provided with a rectangular opening in the upper portion thereof, which opening registers with the opening 23 in the mounting plate 21. An elongate cover member 26 provided with outwardly projecting flanges 27 along each longitudinal edge thereof is attached to the channel member as by screws 28. As shown in Fig. 3, cover member 26 is substantially U-shaped in horizontal section. A flanged cap member 29 is provided at the upper portion of the insulation box and a lower flanged cap member 30 surrounds the lower portion of the gas heat exchanger and closes the lower portion of the insulation box. As shown in Fig. 4 flanges 27 of the cover member 26 are formed with a raised portion 31 between each of the screws 28. The raised portions of the flanges allow the escape of air from the interior of the insulation box when insulating material is being blown into the box thereby assuring a good packing of the insulating material.

In assembling my improved insulation box around the gas heat exchanger 22, the elongate

channel member 25 is attached, as by welding or the like, to the mounting plate 21, the rectangular opening in the channel member being in alignment with the rectangular opening in the mounting plate. Then the gas heat exchanger 22 is located in alignment with the elongate channel member, the upper portion of the heat exchanger is connected to the low and high temperature evaporators and the lower portion of the heat exchanger is connected to the inlet and outlet of the absorber, as stated above. The lower cap member 30 having previously been secured to the lower portion of the gas heat exchanger, the cover member 26 is mounted upon and attached to the channel member 25 by the screws 28. The points of contact between the lower cap member 30, the gas heat exchanger, the channel member 25 and the cover member 26 are sealed by a suitable sealing material which may be a molten fast-setting sealing compound that is poured into the cap member 30. Then the upper cap member 29 is applied to the upper portion of the insulation box and a molten fast-setting sealing compound is poured over the top of this cap member thereby sealing the points of contact between the cap member, the upper portion of the channel member 25 and the upper portion of cover member 26. Insulating material is then blown through an opening, not shown, in the upper portion of the mounting plate 21, which material passes through the closure member 19, through the opening 23 and into the insulation box around the gas heat exchanger 22. The air used to convey this insulating material escapes through the raised portions 31 of the flange members 27 assuring a dense packing of insulation in the insulation box and in the closure member 19. After the insulation box has been blown with the insulating material, a molten fast-setting sealing compound is poured into the joints between the flanges 27 of the cover member 26 and the flange of channel member 25. From the above it is seen that the openings provided by the raised portions 31 as well as all joints between the respective parts of the insulation box, and between the gas heat exchanger and the lower portion of the insulation box, are sealed against the entrance of air.

As an alternative, instead of blowing insulating material into the insulation box, a pad of insulating material such as mineral wool, fiber-glass or the like may be wrapped around the gas heat exchanger before the cover member 26 is applied to the channel member 25, in which case the raised portions 31 may be omitted from the flanges 27 of the cover member 26, and in which case a ribbon of suitable sealing material may be applied between the inner surface of the flanges 27 and the outer surface of the channel member 25. In any event all points of contact of the different elements which make up the insulation box are hermetically sealed by a suitable sealing material so that in the finished product air can not enter the insulation box.

Although I have illustrated and described but one specific modification of my invention, the invention obviously may take other forms and be variously applied within the scope of the following claims.

5 What is claimed is:

1. A refrigerator including a food storage compartment, a vertical flue exterior of said food storage compartment at the rear thereof and a closure member between said food storage compartment and said flue, said closure member including a mounting plate provided with an opening therein, a refrigerating system for cooling said food storage compartment, said refrigerating system including an evaporator in said food storage compartment, a gas heat exchanger in said flue, and means for insulating said gas heat exchanger, said insulating means including a channel member attached to said mounting plate and provided with an opening therein, which opening is aligned with the opening in the mounting plate, said channel member being provided with a contiguous flange along the periphery thereof, a casing mounted on said channel member and adapted to cooperate therewith to encompass said heat exchanger in spaced relation therewith, means for attaching said casing to said channel member, closure members for closing each end of said casing, and insulating material within said casing.

2. A refrigerating apparatus as set forth in claim 1 wherein the casing comprises an elongate member U-shaped in transverse section provided with outwardly projecting flanges along the two longitudinal edges thereof, which outwardly projecting flanges fit within the contiguous flange of the channel member.

3. A refrigerating apparatus as set forth in claim 1 wherein the means for attaching the casing to the channel member includes a pair of flanges, which flanges are provided with raised portions to provide vent openings between the channel member and the casing.

4. A refrigerating apparatus as set forth in claim 1 wherein the casing closure members are in the form of flanged caps that fit within each end of the casing.

5. A refrigerating apparatus as set forth in claim 1 wherein sealing material is provided between the channel member and the casing, between the casing and the closure members and between the gas heat exchanger and at least one of the closure members.

ALBERT SCHULTZE.
